Primary Examiner — Sheryl Lane*Assistant Examiner* — Stacey L Hopkins(74) *Attorney, Agent, or Firm* — Blank Rome LLP(57) **CLAIM**

The ornamental design for a floodlight, as shown and described.

DESCRIPTION

FIG. 1 is a front view of a floodlight of our new design; FIG. 2 is a left view of the floodlight shown in FIG. 1; FIG. 3 is a right view of the floodlight shown in FIG. 1; FIG. 4 is a top view of the floodlight shown in FIG. 1; FIG. 5 is a bottom view of the floodlight shown in FIG. 1; FIG. 6 is a perspective view of the floodlight shown in FIG. 1; and,

FIG. 7 is another perspective view of the floodlight shown in FIG. 1.

Back view of the floodlight is omitted because it has no essential features.

1 Claim, 4 Drawing Sheets(56)
